UNITED STATES PATENT OFFICE.

FRANK BAILEY, OF MINNEAPOLIS, MINNESOTA.

MAIL-DISTRIBUTING BASKET.

1,098,702.

Specification of Letters Patent.

Patented June 2, 1914.

Application filed November 28, 1913. Serial No. 803,453.

To all whom it may concern:

Be it known that I, FRANK BAILEY, citizen of the United States, residing at Minneapolis, in the county of Hennepin and State 5 of Minnesota, have invented certain new and useful Improvements in Mail-Distributing Baskets; and I do hereby declare the following to be a full, clear, and exact description of the invention, such as will enable 10 others skilled in the art to which it appertains to make and use the same.

My invention has for its object to provide an improved mail distributing basket, and, to this end, it consists of the novel devices 15 and combinations of devices hereinafter described and defined in the claims.

In the accompanying drawings, which illustrate the invention, like characters indicate like parts throughout the several views.

20 Referring to the drawings, Figure 1 is a side elevation of the improved basket, some parts being broken away, and some of the exposed parts being shown in section; Fig. 2 is a plan view of the same, some parts being broken away; and Fig. 3 is a transverse vertical section, taken on the line $x^3 x^3$ of Fig. 2.

The body of the basket has a vertically extended flat blade or partition 1 provided, at its intermediate portion, with a long 30 sleeve 2, within which is rigidly secured the upper end of an upright rod 3 held by a clamp 4 on the table Z. This clamp 4 is formed with an upright socket 5 adapted to telescopically receive and rotatively hold the 35 lower end of the rod 3. A set screw 6 is provided for locking the rod 3 within the socket 5. This set screw has screw-threaded engagement with the desk clamp 4, and its inner end is arranged to impinge against the 40 rod 3. On opposite sides of the blade 1 is secured four sets of upwardly and outwardly inclined shelves 7, each set comprising a plurality of shelves vertically spaced, one above the other. Each shelf 7 is provided, at its 45 inner and outer ends, with a relatively high flange 8 and a relatively low flange 9, respectively. The flanges 8 extend the full width of the shelves, while the flanges 9 extend only about one-half of the width 50 thereof.

The shelves 7, as shown, are preferably made detachable, and, hence, provided, at their inner longitudinal edges, with depending flanges 10 that fit in keeper brackets or 55 lugs 11. These keeper lugs 11 are stamped

from vertically extended reinforcing bars 12 secured to opposite sides of the partition 1. At their outer longitudinal edges, the shelves 7 are intermediately cut away, at 13, in order that the letters or papers on the said 60 shelves may be more easily grasped.

When the set screw 6 is loosened, the entire basket is adapted to be swung around in any desired position, and is especially adapted to be used by two persons working on opposite sides of the same desk. By independently and detachably mounting the shelves 7, the shelves of one set may be secured in different vertical positions, one above the other. This mounting of the shelves 7 also 70 permit said shelves to be independently removed from the basket, and the papers filed therein carried from place to place.

From the above description, it is evident that the entire basket may be dismantled 75 and placed within a drawer or other suitable receptacle.

What I claim is:—

1. In a device of the kind described, the combination with a supporting bracket, of 80 a vertical blade rotatively mounted on said bracket, and a pair of reversely inclined shelves supported, one on each side of said blade.

2. In a device of the kind described, the 85 combination with a supporting bracket, of a vertical blade rotatively mounted on said bracket, and a pair of reversely inclined shelves detachably supported, one on each side of said blade.

3. In a device of the kind described, the combination with a supporting bracket, of 90 a vertical blade rotatively mounted on said bracket, and a plurality of reversely inclined shelves detachably supported from opposite sides of said blade, the shelves on one side of said blade being adjustably spaced, one above the other.

4. In a device of the kind described, the combination with a supporting bracket, of 100 a vertical blade intermediately and rotatively mounted on said bracket, and a plurality of reversely inclined shelves supported from opposite sides of said blade.

In testimony whereof I affix my signature 105 in presence of two witnesses.

FRANK BAILEY.

Witnesses:

EVA E. KÖNIG,

HARRY D. KILGORE.
